A. E. MEYER,
COTTON PICKER'S SACK.
APPLICATION FILED DEC. 1, 1919.

1,347,704.

Patented July 27, 1920.

Inventor -
A. E. Meyer,
Kingsport, Tenn.

UNITED STATES PATENT OFFICE.

ADOLPH E. MEYER, OF WEBSTER GROVES, MISSOURI, ASSIGNOR TO TEXTILE PRODUCTS MANUFACTURING COMPANY, OF ST. LOUIS, MISSOURI, A CORPORATION OF MISSOURI.

COTTON-PICKER'S SACK.

1,347,704.

Specification of Letters Patent. Patented July 27, 1920.

Application filed December 1, 1919. Serial No. 341,761.

To all whom it may concern:

Be it known that I, ADOLPH E. MEYER, a citizen of the United States of America, a resident of Webster Groves, in the county 5 of St. Louis, State of Missouri, have invented certain new and useful Improvements in Cotton-Pickers' Sacks, of which the following is a full, clear, and exact description, reference being had to the accompanying drawings, forming a part of this 10 specification.

My invention relates to a sack for use by cotton pickers in gathering cotton in the field, the invention having for its object 15 to produce a cotton picker's sack of very simple and inexpensive nature with the mouth of the sack so formed as to permit easy access to the sack. The sack is preferably of similar structure at each of its sides, 20 thereby permitting a reversal of the sack at any time so that the wear incident to dragging the sack on the ground may not be imposed upon one side of the sack alone, but on both sides of it, to lengthen its serviceability.

Figure I is a front elevation of my cotton picker's sack.

Fig. II is a vertical section.

Fig. III is a top plan with the shoulder 30 strap in section on line III—III, Fig. I.

A designates the body of my cotton picker's sack, open at its upper end to permit access thereto. A shoulder strap B, suitably secured to the upper end of the sack at 35 its edges, serves as a means for supporting the sack on the body of a cotton picker in dragging it upon the ground, as is customary in the use of cotton pickers' sacks.

Each wall of the body A is divided from 40 the upper edge of the wall to a crotch 1, thereby providing a pair of flaps 2 which extend from the side edges of the sack body

to said crotch, the flaps gradually widening inwardly from the side edges toward the division leading to the crotch 1. The pair of 45 flaps 2 at the upper end of each wall of the sack body are provided at their inner ends with clasp or fastening members 3 adapted to be engaged with each other when the flaps are elevated into line with the wall by which 50 they are carried, thereby making said wall continuous to the upper end of the sack body, while the other pair of flaps hangs suspended, as seen in Fig. I.

In the use of my cotton picker's sack, the 55 flaps 2 upon the wall of the body which is intended for the time being to serve as the back wall, are joined by the fastening means provided for their connection, while the flaps upon the front wall hang suspended, 60 and a mouth for the sack is thereby provided which includes a lowered front portion and a back portion projecting higher than the lowered front portion, and the cotton picker may therefore very readily introduce handfuls of cotton into the sack over the front wall of the sack, the elevated rear portion of the sack serving to prevent the picker's hand passing across the mouth of the sack instead of entering thereinto. 70

I claim:

A reversible cotton picker's sack having two walls each divided at its upper end intermediate of its longitudinal edges, providing flaps at opposite sides of the point at 75 which the wall is divided, said flaps being provided with means whereby the flaps carried by either wall may be connected adjacent the line of division in the wall, and a suspension member secured to said longitudinal edges at the upper end of the sack.

In testimony that I claim the foregoing I hereunto affix my signature.

ADOLPH E. MEYER.
